CLAIM

The ornamental design for a multi-station liquid dispensing apparatus, as shown and described.

DESCRIPTION

FIG. 1 is a perspective view of a multi-station liquid dispensing apparatus embodying the invention.

FIG. 2 is a front view of the multi-station liquid dispensing apparatus shown in FIG. 1.

FIG. 3 is a left side view of the multi-station liquid dispensing apparatus shown in FIG. 1.

FIG. 4 is a right side view of the multi-station liquid dispensing apparatus shown in FIG. 1.

FIG. 5 is a top view of the multi-station liquid dispensing apparatus shown in FIG. 1; and,

FIG. 6 is a bottom view of the multi-station liquid dispensing apparatus shown in FIG. 1.

The elements shown in broken lines are included for the purpose of illustrating environment and form no part of the claimed design.
